UNITED STATES PATENT OFFICE.

GUY T. GIBSON, OF NEW ROCHELLE, NEW YORK.

DESIGN FOR A PERFUME BOTTLE.

Application filed December 15, 1925. Serial No. 15,756. Term of patent 14 years.

To all whom it may concern:

Be it known that I, GUY T. GIBSON, a citizen of the United States, residing in New Rochelle, in the county of Westchester and State of New York, have invented a new, original, and ornamental Design for a Perfume Bottle, of which the following is a specification, reference being made to the accompanying drawing, forming part thereof, in which—

Fig. 1 represents a front elevation of a bottle embodying this invention.

Fig. 2 is a top view of the same.

The vertical lines on the stopper, neck and band extending about the top and sides denotes that the glass is colored cerise.

I claim:

The ornamental design for a perfume bottle as shown and described.

GUY T. GIBSON.
